CLAIM

The ornamental design for a valance, as shown and described.

DESCRIPTION

FIG. 1 is a perspective view of a valance showing my new design;

FIG. 2 is a perspective view shown broken away at the center whereby to indicate indeterminate length;

FIG. 3 is a front elevational view shown broken away at the center whereby to indicate indeterminate length;

FIG. 4 is a rear elevational view shown broken away at the center whereby to indicate indeterminate length;

FIG. 5 is a top plan view shown broken away at the center whereby to indicate indeterminate length;

FIG. 6 is a bottom plan view shown broken away at the center whereby to indicate indeterminate length;

FIG. 7 is an elevational view, showing one of two identical ends; and

FIG. 8 is an enlarged fragmentary view showing the upper left hand corner of the valance of FIG. 3 in greater detail.
